DESIGN FOR TEXTILE FABRIC

Samuel E. Staines, Ridgewood, N. J., assignor to
Botany Worsted Mills, Passaic, N. J., a cor-
poration of New Jersey

Application December 13, 1937, Serial No. 73,562

Term of patent 14 years

To all whom it may concern:

Be it known that I, Samuel E. Staines, a citizen of the United States, residing at 309 Stevens Avenue, Ridgewood, in the county of Bergen and State of New Jersey, have invented a new, original, and ornamental Design for Textile Fabrics, of which the following is a specification, reference being had to the accompanying drawing, forming part thereof.

The figure of the drawing is a plan view of a piece of textile fabric having the design woven therein.

The design of the present invention presents

the appearance of pairs of oppositely inclined herringbone weaves, each one of the members of the pair being bounded by nubbed stripes and each having two nubbed stripes extending across the herringbone ribs between and parallel to the boundary stripes, the nubs of all of the stripes being more or less irregular in size and spacing along the stripes.

I claim:

The ornamental design for textile fabric, as described and shown.

SAMUEL E. STAINES.
